UNITED STATES PATENT OFFICE.

ROBERT H. PRATT, OF MAMARONECK, NEW YORK, ASSIGNOR TO THE WHEELER CORRUGATING COMPANY, OF WHEELING, WEST VIRGINIA.

DESIGN FOR A FINISHING-PLATE.

SPECIFICATION forming part of Design No. 23,915, dated December 25, 1894.

Application filed November 30, 1894. Serial No. 530,494. Term of patent 14 years.

To all whom it may concern:

Be it known that I, ROBERT H. PRATT, a citizen of the United States, residing at Mamaroneck, in the county of Westchester and State of New York, have invented and produced a new and original Design for Finishing-Plates for Buildings, of which the following is a specification, reference being had to the accompanying drawing, which shows a metallic finishing-plate for buildings made in accordance with my design.

The leading features of my design are the festoons A, the scrolls B and the horn-shaped figures C, combined and arranged as shown 15 in the accompanying drawing. The festoons,

scrolls and horn-shaped figures are ornamented and they are interspersed with conventionalized acanthus leaves D, and minor ornamentations, all of which are clearly shown in the drawing.

I claim—

The design for a finishing plate herein shown and described.

In testimony whereof I have hereunto subscribed my name.

ROBERT H. PRATT.
